United States Patent Office.

B. F. SOUTHGATE, OF BRIDGEWATER, VERMONT.

Letters Patent No. 68,588, dated September 3, 1867.

IMPROVEMENT IN DIAMOND KEY.

The Schedule referred to in these Letters Patent and making part of the same.

TO ALL WHOM IT MAY CONCERN:

Be it known that I, B. F. SOUTHGATE, of Bridgewater, Windsor county, Vermont, have invented a new and improved Diamond Key; and I do hereby declare that the following is a full, clear, and exact description thereof, which will enable others skilled in the art to make and use the same, reference being had to the accompanying drawings, forming part of this specification.

This invention relates to an improved key for holding cranks, shafts, and other machinery, and consists in a wedge-shaped key, the section whereof is a diamond fitting into a V-groove in the crank or shaft, and into a V-groove, corresponding thereto, in the bearing.

The accompanying drawing is a perspective view of my improved diamond key.

A is a shaft, or crank, or other piece of machinery; B, a bearing, to which it is to be keyed. C is my improved diamond and wedge-shaped key. A V-shaped groove is made in A to receive the key, a corresponding V-shaped groove existing in the bearing B.

This form of key is specially adapted for use when the work has to be done with chisel and file, and especially where there is a backlash motion. Should the key become loose, or be too small for the groove, a strip of brass, b, may be inserted, as shown, and the key driven up against it.

Having thus described my invention, what I claim as new, and desire to secure by Letters Patent, is—

The diamond key C, fitting in V-shaped grooves in shaft and bearing, or their respective equivalents, in manner and for the purposes substantially as described.

B. F. SOUTHGATE.
